UNITED STATES PATENT OFFICE.

JOSEPH H. DEARBORN, OF LAKESIDE, OHIO.

CARBURETER.

1,290,109.

Specification of Letters Patent.

Patented Jan. 7, 1919.

Application filed May 18, 1917. Serial No. 169,387.

To all whom it may concern:

Be it known that I, JOSEPH H. DEARBORN, a citizen of the United States, residing at Lakewood, in the county of Cuyahoga and State of Ohio, have invented certain new and useful Improvements in Carbureters, of which the following is a specification.

This invention relates to carbureters in general and the broad principle involved is adaptable wherever hydrocarbon products are employed as a heating or explosive medium, or where it is desirable to combine the volatile vapors which evaporate from the hydrocarbon products with proper proportions of air to produce a uniform combustion of the inflammable mixture. The improvement with modifications of construction is applicable to blast furnaces, steam boilers, or hydrocarbon burners in general, but as it is particularly serviceable in connection with internal combustion engines it is herein shown and described as an embodiment of a carbureter of this character, the purpose of which is to provide means for combining the volatile vapors which evaporate from the hydrocarbon liquids used with proper proportions of air to form an inflammable gas the explosion of which actuates the pistons and thereby drives the engine. If the mixture is too rich or too lean the energy of the explosion is reduced and the amount of power applied to the piston is decreased proportionately.

The control of the engine is governed by altering the speed through regulation of the supply of gas to the cylinders. The engine should run from its lowest to its highest speed without any irregularity in torque, that is, the acceleration should be gradual rather than spasmodic. As the degree of compression varies in value with the amount of throttle opening the conditions necessary to obtain maximum power differ with varying engine speeds. When the throttle is barely opened the engine speed is low and the gas must be richer in fuel than when the throttle is wide open and the engine speed is high. When an engine is turning over slowly on low throttle the compression has low value and the conditions are not so favorable to rapid combustion as when the compression is high. At high engine speeds the gas velocity through the intake is higher than at low speeds, and regular engine action is not so apt to be disturbed by condensation of liquid in the manifold due to

excessive rich mixture or a superabundance of liquid in the stream of carbureted air.

Neither a too rich or a too lean mixture is desirable as the engine will be hard to start and lack power on a lean mixture and it will tend to overheat and be wasteful of fuel as well as promoting carbon deposits if the mixture is too rich.

The principal object of the present invention is the provision of a carbureter of great elasticity of operation, that is one by means of which the engine will work smoothly over a wide range of speeds; that works automatically in sympathy with the engine speeds; and that will respond quickly in starting; that not only supplies a certain amount of gas, but that delivers a mixture to the cylinders that is accurately proportioned and of proper composition at all engine speeds.

With the above mentioned and other apparent objects in view the invention consists principally in the provision of a flexible or automatically expanding venturi which operates with the other elements of the device to produce the desired results as set forth.

In the accompanying drawing forming a part of this specification Figure 1 is a central vertical section of a carbureter embodying the improvement and adaptable to internal combustion engines. Fig. 2 is a fragmentary section showing certain of the elements in a position which they assume in the operation of the device. Figs. 3 and 4 are plan views of the venturi detached and showing said elements in the expanded and contracted positions, respectively, and Fig. 5 is a fragmentary sectional view of a modified construction of venturi.

Throughout the drawings and in the description similar characters of reference are employed to designate similar parts.

Referring to the drawing, 1 represents the ordinary carbureter float chamber connected with the fuel supply source through the nipple 1^a, and connected by means of conduit 2 with the nozzle 3 which projects centrally into the Venturi or mixing chamber 4^a. 5 represents the air inlet which surrounds the nozzle 3 and connects with the lower terminal of the Venturi member 4. 6 is the throttle chamber provided with the throttle member 7 and connected with the upper terminal of said Venturi member 4. The features thus far described, with the ex-

ception of the Venturi member, are substantially the same in construction and arrangement as is common to carburetors heretofore used in connection with internal combustion engines, therefore the functions of the common elements need not be dwelt on only in so far as their co-action with the Venturi member is concerned, as the present invention lies in the construction and operation of said venturi.

As hereinbefore mentioned, the broad principle of the invention consists in an automatically expanding and contracting venturi. This principle is carried out in a 15 preferred embodiment as illustrated. The Venturi member 4 is interposed between the air inlet 5 and the throttle chamber 6, the mixing chamber 4^a being arranged concentric with the fuel nozzle 3. The wall of 20 the chamber 4^a is made up of alternate rigid and flexible elements. The rigid elements 4^b are in section substantially the form as shown in Fig. 1, being contracted in the horizontal plane a—a near the outlet of nozzle 3, and flaring to the air inlet 5 and also to 25 the throttle chamber 6 as shown by contours 4^c and 4^d. The alternate flexible elements comprise leaves 8 which are mounted on fixed bearings 8^a and are retained in their 30 predetermined normal position by stops 8^b and adjustable spring members 9 mounted on fixed pins 9^a, said springs being adjusted by screws 10 bearing on the members 9^b.

Fig. 4 shows the relative position of the 35 flexible and rigid elements of the venturi when in normal condition with the mixing chamber 4^a contracted. This condition exists when the throttle is closed and when nearly open, at which time it is desirable to 40 have a rich mixture. The mixing chamber being contracted admits the minimum volume of air required. When the throttle is barely open the velocity of the air through the inlet 5 to the chamber 4^a is low and as the 45 throttle opening is increased the velocity is increased proportionately. The pressure of the air from the inlet 5 on the leaves 8 causes them to rock on the bearings 8^a thereby increasing the lateral dimensions of the chamber 4^a and accommodating a greater volume 50 of air. As the expansion of the Venturi chamber is proportionate to the velocity of the air intake, and as the said velocity is governed by the throttle opening, the throttle 55 also controlling the speed of the engine, the result is the automatic expansion of the venturi in sympathy with the speed of the engine thereby automatically delivering a mixture to the cylinders that is accurately 60 portioned or of proper composition at all engine speeds.

I have conceived devices differing considerably in details of construction that may be employed for the purpose set forth, without departing from the spirit of the invention.

tion or the scope of the appended claims. The construction as above described is applicable to the type of carburetor illustrated, but I anticipate that the details of construction would necessarily have to be modified to 70 suit other types or to meet different conditions. Fig. 5 is an example of a modification wherein the movable members 80^a are actuated by the pressure from the inlet 50, and regulated by the spring members 90, 75 thereby providing an automatically expanding venturi.

It will readily be seen that whether the actuating medium is the air or the other gases that combine to produce the desired 80 result, the broad principle is the same, therefore I am not confined to the construction as shown and described, the limitation being governed by the scope of the claims.

What I claim and desire to secure by Letter Patent is—

1. In a carburetor, an expanding venturi comprising a series of rigid filler members 90 annularly arranged, said filler members alternately disposed between units of a series 95 of radially expansible members, the parallel surfaces of said expansible members bearing on opposite faces of the filler members, the combined series forming a chamber annularly closed under all conditions contracted 95 in the approximate horizontal plane of the fuel orifice provided in the carburetor, and flaring therefrom to the end openings of said chamber.

2. In a carburetor, an expanding venturi 100 comprising a series of rigid filler members annularly arranged, said filler members alternately disposed between units of a series 105 of radially expansible spring members, the longitudinally parallel edges of said expansible spring members bearing on opposite faces of the filler members, the combined series forming a chamber annularly closed under all conditions contracted in the approximate plane of the fuel orifice provided 110 in the carburetor, and flaring therefrom to the ends of said chamber.

3. A carburetor for internal combustion engines, including an air inlet and a throttle chamber, a venturi interposed between said inlet and chamber, a fuel nozzle provided with an orifice centrally located in the venturi, said venturi comprising a series of filler members 115 annularly arranged, said filler members alternately disposed between units of a 120 series of flexible, spring-controlled members, the parallel surfaces of the expansible members bearing on opposite surfaces of the filler members, the combined series forming a venturi annularly closed under all conditions, contracted in the approximate plane 125 of the fuel orifice and flaring therefrom to the air inlet and to the throttle chamber.

4. In a device for mixing hydro-carbon fuel products with air in proper proportion 130.

for combustion, the elements being under varying velocities, the combination of an air inlet and a fuel inlet; a mixing chamber connected with said inlets, said mixing chamber formed by radially movable members annually disposed and automatically operated by air pressure, rigid members interposed annularly between said

movable members and bearing on parallel sides thereof, the combined movable and rigid members forming a venturi annularly closed under all conditions, contracted in the approximate plane of the fuel inlet and flaring therefrom to the ends.

In testimony whereof I affix my signature. 15
JOSEPH H. DEARBORN.
